UNITED STATES PATENT OFFICE.

FRANK W. SHIELDS, OF WALLA WALLA, WASHINGTON, ASSIGNOR TO VALLEY FRUIT COMPANY, OF WALLA WALLA, WASHINGTON, A CORPORATION.

CAR DECK.

Application filed March 17, 1925. Serial No. 16,111.

To all whom it may concern:

Be it known that I, FRANK W. SHIELDS, a citizen of the United States, residing at Walla Walla, in the county of Walla Walla and State of Washington, have invented certain new and useful Improvements in Car Decks, of which the following is a specification.

This invention relates to sectional ventilating car decks and has as one of its objects to provide a car deck that may be constructed at odd moments and that will be adapted to refrigerator cars, and the like, with a minimum of cutting and fitting during installation.

Another object of the invention is to provide a car deck that may be secured rigidly in refrigerator cars, and other cars using insulation in their make up, without nailing the deck to the car with the resulting mutilation of the walls and puncturing the insulation.

A further object of the invention is to provide a car deck having strength, rigidity and immobility and that may be secured in a car by means of wedges, and to utilize certain of the wedges to complete a continuous platform throughout the full length of the car.

A further object of the invention is to provide a car deck which may be installed as the car is loaded.

A further object of the invention is to provide a car deck whose method of construction is utilized to enable perfect ventilation to obtain throughout the load.

A further object of the invention is to provide a deck that is relatively cheap to construct and which may be assembled without the use of skilled labor.

With these and other objects in view reference is now had to the accompanying drawings in which—

Fig. 1 is a longitudinal section of a car showing the car deck in place;

Fig. 2 is a perspective view of the car deck assembled;

Fig. 3 shows an end elevation of the car deck;

Fig. 4 is a sectional view taken through the center of the car; and

Fig. 5 is a perspective view of one of the panels showing details of construction.

Having reference to the drawings like

numerals refer to like parts throughout the several views and the numeral 1 refers to a car having the usual sides 2 and 3 respectively, and ends 4 and 5 respectively, a floor 6, a roof 7, a centrally positioned doorway 8, and wheels 9 resting on a track 10.

In transporting onions and other produce by rail it is essential that ventilation be provided to prevent the produce from heating and sweating, and that provisions be made to load more in the car than would rest on the floor alone.

For this purpose then a deck 11 is provided which consists principally of panels 12 wherewith to support the platform 13 of the deck with great rigidity and immobility.

The panels consist of a plate 14 to which uprights 15 are rigidly secured by any suitable means as by nailing, and on top of the uprights is a sill 16 also nailed securely to the uprights.

The uprights are as few in number as will support the load and to strengthen the plate and sill in the span between the uprights, web members 17 and 18 respectively are provided as shown.

The webs are securely nailed to the plate 14 and sill 16 and both webs are positioned on the same side of the panel to form a bearing plate against the side of the car, and the webs also provide a space between the side of the car and the uprights to provide for a circulation of air at this point of the load.

As the car lengths obviously vary the panels are made up in lengths that will not exceed the distance from the end of the car to the near side of the car door, and the space 19 or runway, in between the panels, i. e. opposite the door may thus be left for use in a manner and for a purpose to be explained.

It will be understood from the above that the panels may be constructed during the slack periods and made of a standard size, the length being determined by the shortest car, and the height being the height of the sacks containing the produce plus a space for ventilation as shown in Fig. 4.

In Fig. 1 is shown the deck installed in a car whose length is greater than the minimum showing the relative position of the panels with respect to the distance between the ends and the near side of the car door.

The assembling of the deck 11 will now be described and the various members which

go to complete the deck will be considered in their order:

In assembling, two panels are placed against one side of the car with their back ends 20 resting against the respective ends of the car, and two panels are similarly placed on the opposite side of the car. The two opposite panels are now secured in a vertical position, with the webs resting 5 against the side of the car, by means of the end cross tie 21 that is nailed to the uprights at the ends 20, and on the inside thereof to keep the produce away from the end wall thus providing for ventilation at 10 that point.

Where the width of the car demands a center support 22 for the platform 13 a third panel is placed in the center between the two opposite panels, and this panel is 20 likewise secured in a vertical position by the cross tie 21, the cross tie being nailed to it in the manner above explained.

Loading is now commenced and proceeded with through the runway 19 left between 25 the inner ends 23 of the panels, the runway being left clear and free of all obstructions so that trucks may be used to convey and deposit the goods on the floor against the cross tie and the panels.

30 As a certain amount of the floor space is covered the second cross tie 24 is secured in place, and the platform consisting of boards 25 laid in a manner to provide spaces 26 therebetween, is laid up to this point, and 35 this part of the platform is then loaded.

Loading and assembling now continues in the same manner until both ends of the car are filled when wedge posts 27 are driven in between the floor and the roof and against 40 the ends 23 of the respective panels, to be there secured by nailing in the usual manner, and these wedge posts maintain the panels in a fixed vertical position.

The wedge posts are cut to reach the ceiling of the car and obviously therefore the labor of cutting will be the same whether the car has a pitched ceiling as shown, or a level ceiling (not shown).

Now a wedge plate 28 is placed on the 50 floor, on the far side of the runway, and forced into place between the lower part of the wedge posts 27 thus forcing the back ends 20 of the panels against the ends of the car. Filler pieces 29 are then nailed to the 55 opposite wedge posts and a wedge beam 30 is driven into place down onto the filler pieces to force the sill, or upper part of the panels, against the ends of the car thus positively securing the panels in a fixed position longitudinally.

The near end of the runway may now be loaded, the second wedge beam 31 and the third wedge beam 32 driven into place as the before mentioned wedge beam 30, and 60 the boards 25 laid thereon.

This forms a complete and continuous platform throughout the length of the car.

It will now be noted that the load is divided into relatively small sections, each section being bounded by the panels 12 and 70 the ties 21 and 24, etc., and that ventilation may occur around the uprights and the cross ties, over the top of the sacks 34, in the space 35, the latter supplying ventilation to counteract the effect of a tight floor; and that a perfect ventilation is supplied through the open platform and between the sacks loaded thereon.

It is also obvious that with the respective panels provided with webs, ample strength 80 to the platform is obtained; that the system of wedging positively precludes the possibility of the deck falling, due to the movement of the car and load in transit; and that assembling and loading requires a 85 minimum of effort and expense.

It is also obvious that as all nailing is straight work, i. e. as there is no toenailing, that it is just as simple to remove the load and deck as it was to construct and load. 90

Where cars are equipped with false floors (not shown) it is obvious that such a floor would only effect the length of the wedge posts, and while such a floor might add to the ventilation this would be an advantage 95 rather than a detriment.

Having thus described my invention, I claim—

1. In a car deck, a plurality of panels positioned vertically in a car, means to 100 maintain said panels vertically, said panels forming a support for a platform, vertically positioned wedge posts rigidly attached to said panels and secured between the floor and roof of said car, and longitudinally 105 positioned wedge beams secured between the panels to force said panels against the ends of the car, said beams forming a support for an additional platform.

2. In a car deck, a plurality of panels 110 positioned vertically in both ends of a car, means to maintain said panels vertically, said panels forming a support for a platform in each end of a car, vertically positioned wedge posts rigidly attached to the 115 inner ends of said panels and forming a wedge between the floor and roof of said car, and longitudinally positioned wedge beams placed between the respective panels to force said panels against the ends of said car, said beams forming a support for a central platform to complete a continuous platform throughout the length of the car.

3. In a car deck, a plurality of panels positioned vertically in both ends of a car, 125 two of said panels being positioned against one side of said car and against the respective ends thereof, and two of said panels being similarly placed on the opposite sides of said car, said panels being of a length 130

- to provide a runway in the center of said car and between the inner ends of said panels, means rigidly attached to the opposite panels, to maintain said panels in a vertical position to provide supports for a platform in each end of said car, vertically positioned wedge posts rigidly attached to the inner end of said panels and forming a wedge between the floor and roof of said car, to maintain said panels in a fixed position vertically, and longitudinally positioned wedge beams placed between the respective panels of both ends of the car to force said panels against the ends of said car to maintain said panels in a fixed position longitudinally, said beams forming a support for a central platform to complete a continuous platform throughout the length of the car.
4. In a car deck, a plurality of panels having webs attached to one side thereof to provide for ventilation, and positioned vertically in both ends of a car, two of said panels being positioned against one side of said car and against the respective ends thereof, and two of said panels similarly placed on the opposite side of said car, said panels being of a length to provide a runway in the center of said car and between the inner ends of said panels, central panels positioned between said oppositely disposed panels, means rigidly attached to said panels to maintain said panels in a vertical position to support a ventilating platform in each end of said car, vertically positioned wedge posts rigidly attached to the inner ends of said panels, and forming a wedge between the floor and roof of said car to maintain said panels in a fixed vertical position, and longitudinally positioned wedge beams placed between the respective panels of both ends of the car, to force said panels against the ends of the car and to maintain said panels in a fixed position longitudinally, said beams forming a support for a central ventilated platform to complete a continuous platform throughout the length of the car.
5. In a car deck, a plurality of panels, each panel comprising a plate, uprights rigidly attached to said plate, a sill rigidly attached to the top of said uprights, and a pair of wedge members rigidly attached to one side of said panels, and to the plate and sill respectively, said panels being positioned vertically in both ends of said car, with two of said panels positioned against one side of said car and against the respective ends thereof, and two of said panels similarly placed on the opposite side of said car, said panels being of a length to provide a runway in the center of said car and between the inner ends of said panels, means rigidly attached to the opposite panels to maintain said panels in a vertical position, with the webs thereof resting against the side of the car, an open platform mounted on said panels, means to support the center of said platform, vertically positioned wedge posts rigidly attached to the inner ends of said panels to form a wedge between the floor and roof of said car, to maintain said panels in a fixed vertical position, and longitudinally positioned wedge beams placed between the respective panels to force said panels against the ends of said car to maintain said panels in a fixed position longitudinally, said beams forming a support for a central platform to complete a continuous platform throughout the length of the car.
6. In a car deck, the combination with a car, of a plurality of panels, a platform mounted on said panels to form a deck, and means to secure the deck in the car laterally, vertically and longitudinally without nailing to the car, said means comprising laterally positioned cross ties, vertically positioned wedge posts, and longitudinally positioned wedge beams, secured to said panels.
7. In a car deck, the combination with a car, of a plurality of panels positioned vertically in a car, means to maintain said panels vertically without attaching them to a car, said panels forming a support for a platform, vertically positioned wedge posts rigidly attached to said panels and secured in place by wedging between the floor and roof of the car, and longitudinally positioned wedge beams placed between the ends of the panels to secure said panels horizontally by wedging between the ends of said car, said means forming a support for an additional platform.

In testimony whereof I affix my signature.

FRANK W. SHIELDS.
